UNITED STATES PATENT OFFICE.

GEORGE T. MCLEOD, OF DEDHAM, MASSACHUSETTS, ASSIGNOR TO THOMAS G. PLANT,
OF BOSTON, MASSACHUSETTS.

HEEL-EDGE LINER.

957,993.

Specification of Letters Patent. Patented May 17, 1910.

Application filed May 7, 1909; Serial No. 494,535. Renewed April 4, 1910. Serial No. 553,293.

To all whom it may concern:

Be it known that I, GEORGE T. MCLEOD, a citizen of the United States, residing at Dedham, in the county of Norfolk and State of Massachusetts, have invented an Improvement in Heel-Edge Liners, of which the following description, in connection with the accompanying drawings, is a specification, like figures on the drawings representing like parts.

The invention to be hereinafter described relates to machines for treating the heels of boots and shoes. As well known by those skilled in the art, when the breast of a heel is scoured or treated in the usual course of manufacture, the edges or corners of the heel extending from the tread surface to the sole of the boot or shoe are left more or less rough or uneven and sometimes with a bur of untrimmed material projecting therefrom; and at the point of union or connection between the heel at the base of the said edges or corners and the sole of the shoe a pronounced bur or bunch of untrimmed material is usually present. It has been common to trim or line up the edges of heels and remove the burs or bunches by means of a knife in the hands of the operator, an operation obviously slow, expensive, and unsatisfactory owing to the non-uniformity of the resulting product.

With these facts in mind the aims and purposes of the present invention have been to provide means for trimming or lining up the edges or corners of the heel extending from the tread surface to the sole, which shall be economical and rapid in operation, and which will serve to effectually remove any bur or bunch of material along the edges or corners of the heel and at the connection or union of the heel with the sole, all as will hereinafter more fully appear.

In the drawings:—Figure 1 is a side elevation of a sufficient portion of a shoe treating machine to illustrate the present invention and its associated parts; Fig. 2 is a side view, parts being in section, showing a shoe, the heel of which is being treated by the heel edge liner; Fig. 3 is a sectional perspective showing the heel liner detached; and Fig. 4 is a sectional view on line 4—4, Fig. 1.

Mounted upon suitable supports 1 is a shaft 2, preferably provided with a driving pulley 3 disposed between suitable shaft

bearings 4 and driven from any suitable source of power by the belt 5, or otherwise.

A cleaning or polishing brush 6 may be secured to the shaft 2 for use as circumstances may dictate, though obviously such brush is not an essential element of the invention.

The shaft 2 is provided with the heel edge liner of the present invention, and said liner may be secured to rotate with the shaft in any usual or desired manner. In the present embodiment of the invention the end portion of the shaft 2 is preferably screw threaded, as at 7, Fig. 3, and has a collar 8 thereon, the face 9 of which may be countersunk as 10, to receive the boss 11 of a liner support 12. The liner support 12 may be variously formed, but in the present illustration of the invention is of general conical form, having a face 13 disposed in a plane transversely of the shaft 2. A nut 14, screw-threaded to the end of the screw-threaded portion 7 of the shaft 2, serves to clamp the liner support 12 against the collar 8, as will be readily understood.

As hereinbefore noted, the liner support 12 is preferably provided with a boss or shouldered portion 11, and said boss or shouldered portion may serve as a centering element for a disk 15 of abrading material, such as sand paper, emery, or the like, suitable for acting upon the material of the heel. In the present invention the disk 15 of sand paper, emery, or the like is made separate from the liner support 12 and provided with a central aperture, as will be understood, to engage the boss 11, so that when the disk of abrading material 15 is placed upon the face 13 of the liner support 12, and the latter slid upon the end 7 of the shaft 2 into co-acting relation with the collar 8, the face 9 of said collar 8 and the face 13 of the liner support will serve as a clamp for holding the disk of abrading material 15 firmly in place so as to rotate with the shaft.

Extending around the periphery of the face 13 of the liner support 12 is a cutting ring 16, Figs. 3 and 4, said cutting ring 16 being formed either as part of the liner support 12 or secured thereto and projecting slightly therefrom, as indicated in Fig. 2. The cutting edge of the cutting ring 16 and the face of the abrading material 15 are or may be substantially in the same

transverse plane, though of course the invention contemplates some variation in this respect, and said cutting ring 16 is provided with alternate cutting or toothed portions 5 17 and smooth portions 18, Figs. 3 and 4, the construction being such that when an edge or corner of a heel is presented to the action of the abrading disk 15 and the cutting ring 16, as indicated in Fig. 2, the 10 said disk 15 of abrading material will act along the edge or corner of the heel from the tread thereof to a point near the connection of the heel with the sole and at this point, which requires a different character of treatment, as well understood by those skilled in the art, the cutting ring 16 acts to remove any bur or projection of material.

The cutting ring 16 may be preferably formed of metal and in case the liner support 20 12 be also formed of metal, the said cutting ring may be formed integral therewith, or if the liner support be formed of other material, the cutting ring 16 may be formed of metal and secured thereto in any 25 usual manner.

In the operation of the device, the operator takes the shoe in his hand and presents an edge or corner of the heel to the action of the liner device, comprising the 30 disk of abrading material 15 and the cutting ring 16, so that from the tread portion of the heel to the point near the connection of the heel to the sole, the disk of abrading material during its rapid rotation will act 35 upon the corner of the heel to remove any bur or bunch of untrimmed material, and the cutting ring 16 will simultaneously act upon the portion of the heel adjacent the sole or "connection" to remove the usual 40 bunch or bur at this point.

Of course it will be obvious that various changes in the form or disposition of the parts may be made within the true scope of the present invention which is definitely set 45 forth by the claims.

What is claimed is:

1. In a heel edge liner, a shaft, means for rotating the shaft, a disk of abrading material secured to said shaft to act along the 50 edge or corner of a heel presented thereto, and a cutting ring closely surrounding said disk of abrading material and forming a peripheral edge thereto to remove any bur or bunch of material at the connection of 55 the heel with the sole.

2. In a heel edge liner, a shaft, means for rotating the shaft, a disk of abrading material secured to said shaft to act along the edge or corner of a heel presented thereto, 60 and a cutting ring forming a peripheral

edge to said abrading material and having cutting edge portions surrounding said disk of abrading material to remove any bur or bunch of material at the connection of the heel with the sole. 65

3. In a heel edge liner, a shaft, means for rotating the shaft, a disk of abrading material secured to said shaft to act along the edge or corner of a heel presented thereto, and an independent cutting ring having cutting edge portions alternating with smooth portions and surrounding said disk of abrading material to remove any bur or bunch of material at the connection of the heel with the sole. 70

4. In a heel edge liner, a shaft, means for rotating said shaft, a liner support having a face extending in a plane transversely of said shaft, a disk of abrading material rotating with said shaft and bearing on the 80 said face of the liner support, and a cutting ring on the liner support surrounding the disk of abrading material to act upon the heel at the connection with the shoe sole. 75

5. In a heel edge liner, a shaft, means for rotating said shaft, a liner support having a face extending in a plane transversely of said shaft, a clamping collar on said shaft, a disk of abrading material disposed between the clamping collar and face of the liner support to act along the edge or corner of a heel presented thereto, and a cutting ring surrounding said disk of abrading material to act upon the edge or corner of the heel at the connection with the sole. 85

6. In a heel edge liner, a shaft, means for rotating the shaft, a liner support having a cutting face extending in a plane transversely of said shaft, and a cutting ring disposed about the edge of the liner support to 100 act upon the edge or corner of a heel at the connection with the sole of a shoe to remove any bur or bunch at that point.

7. In a device of the character described, the combination of a shaft, means for rotating said shaft, and a heel edge liner rotating with said shaft and having a cutting face for acting along the edges or corners of a heel and a cutting edge having alternate plain and cutting portions to act at the connection of the heel with the sole to remove burs or bunches and line up the heel edges. 110

In testimony whereof, I have signed my name to this specification, in the presence of two subscribing witnesses.

GEORGE T. McLEOD.
